[57] CLAIM

The ornamental design for a dough-scraper, as shown and described.

DESCRIPTION

FIG. 1 is a front perspective view of a dough-scraper showing my new design, the rear opposite view being a mirror image thereof;

FIG. 2 is a front perspective view of a modification of my dough-scraper of FIG. 1, the rear opposite view being a mirror image thereof;

FIG. 3 is a right side elevational view of the dough-scraper of FIG. 1;

FIG. 4 is a front elevational view thereof;

FIG. 5 is a left side elevational view thereof;

FIG. 6 is an end elevational view thereof from the blade end;

FIG. 7 is a right side elevational view of the dough-scraper of FIG. 2;

FIG. 8 is a front elevational view thereof;

FIG. 9 is a left side elevational view thereof; and,

FIG. 10 is an end elevational view thereof from the blade end.
